SYSTEM FOR REMOTELY CONTROLLING A
RADIO RECEIVER

Albert S. Blatterman, Asbury Park, N. J.

Application April 30, 1931, Serial No. 534,080

6 Claims. (Cl. 250—20)

This invention relates to a system for effecting the entire remote control of a radio receiver or other apparatus from a remote point over the power or lighting lines which supply the receiver or apparatus itself with operating power.

In general, the present invention is a carrying forward of the remote control system of the type described in my Patent No. 1,856,310, March 3, 1932, in which the entire operation of the radio receiver including its tuning, its volume of response regulation, and the turning of the receiver on or off is accomplished by means of a readily portable control unit which is connected to the usual house lighting lines and which, broadly speaking, comprises a generator of high frequency oscillations which are constrained to flow over the light lines to the point where the receiver is located, the control of the receiver being accomplished by these oscillations as described in the patent aforesaid. In that connection, however, it is pointed out that the present invention has general application to any system of remote control operation in which the control is accomplished by the use of high frequency currents transmitted from a control point over electrical conductors to the point where the apparatus is to be contained or located. Since high frequency oscillatory currents exist in systems of the class herein referred to, and since in general such systems are responsive over a relatively wide band of frequencies, it is to be expected that certain interference effects may normally be experienced not only on the receiving system which is itself being remotely controlled, but on other receiving sets in the neighborhood.

Accordingly, a primary object of the invention is to carry forward the essential principles and features of the patent hereinbefore referred to and to provide methods and means for preventing various kinds of interference that may be encountered in the practical use of such remote control systems.

Other objects of the invention will more readily appear as the nature of the invention is better understood, the same consisting in the novel construction, combination and arrangement of parts hereinafter more fully described, illustrated and claimed.

Certain preferred and practical embodiments of the invention are shown in the accompanying drawings in which:

Figure 1 is a diagrammatic view illustrating certain of the elements of a remote control system of the class hereunder consideration.

Figure 2 is a diagram illustrating a modifica-

tion of the circuit arrangements whereby interference in neighboring circuits is prevented.

Figure 2a is a diagram illustrating a further modification by which interference in neighboring circuits is prevented.

Figure 2b illustrates, diagrammatically, a third modification which prevents interference in neighboring circuits.

Figure 3 is a diagram illustrating, schematically, remote control systems located in adjacent apartments.

Figure 4 is a diagram illustrating two adjacent interconnected remote control systems, together with means which I have invented to prevent interference between the two systems.

Figure 5 is a detailed diagrammatic view illustrating one of the interference preventing elements used in Figure 4.

Figure 5a illustrates a modification of the interference preventing element shown in Figure 5.

Figure 6 is a diagram explaining the elimination of conjugate signal beat interference.

Figure 7 is a diagram explaining the suppression of cross-modulation interference.

Figure 8 is a diagram illustrating a circuit arrangement by means of which short wave interference is prevented.

Figure 9 is a diagram illustrating a further modification of the invention by which short wave interference is prevented.

Figure 10 is a diagram showing a circuit used for the regulation of receiver sensitivity by remote control.

Figure 11 is a diagram illustrating a further modified form of circuit for the regulation of receiver sensitivity by remote control.

Figure 12 is a diagram illustrating a practical embodiment of the invention in a complete remote control system.

Referring to the type of remote control system set forth in Patent No. 1,856,310, certain of the interference difficulties that may be experienced in the practical use of such systems, together with remedial measures to reduce or eliminate such interference when it is encountered, will be briefly explained. For convenience the several types of interference may be classified under the following general headings, viz: (1) Antenna radiation; (2) Cross-talk between circuits; (3) Conjugate signal beats; (4) Cross-modulation; (5) Image signals; (6) Harmonic interference; (7) Static and background interference.

Antenna radiation.—In the class of remote control systems hereunder consideration, it will be observed from Figure 1, that high frequency cur-

rent is transmitted from the remote control device C over the house lighting lines L², L³ to a pick-up coil system 3—4 and thence to ground at G. G' indicates the electric companies' ground on the lines. The high frequency current referred to passing through coil 3, induces a high frequency voltage in the associated coil 4 which, as seen in Figure 1, is connected to the antenna A and also to the ground G. As a result, therefore, the high frequency voltage in the coil 4, produced as described by the high frequency remote control line current, produces a similar high frequency current in the antenna-ground system and the latter as a consequence acts like a low power transmitting station radiating high frequency energy which may cause interference in neighbor receivers.

In order to overcome this class of interference it is proposed to carry forward the principles of the aforesaid copending patent, and for the typical and common case of broadcast reception for example, to select the remote control frequency or frequencies transmitted over the light lines to be either above or else below the band of frequencies used for broadcasting and, at the same time making such other concomitant apparatus arrangements as may be required by such frequency selection in accordance with the principles and features prescribed for such control current frequencies in my aforementioned copending patent. Under these conditions it will be clear that any antenna radiations of the kind referred to will cause no neighborhood interference within the broadcasting spectrum because such radiation will then occur at frequencies beyond the frequency range of neighboring broadcast receivers.

Another remedy proposed to overcome this class of interference is illustrated in Figure 2 wherein an additional vacuum tube 5 is employed in the mixing box with its grid connected to input coil 7 and antenna A. Signals from the antenna are repeated into the plate circuit of the tube 5 where they are in this case mixed with the high frequency control currents coming from lines L² and L³ through coupling condenser 6, and both the antenna frequency and the control frequency are then impressed, as will be seen from the drawings, upon the detector tube 1 by means of the broad band or untuned transformer 3—4. In Figure 2, other circuit elements which might have been shown to the left of tube 1 are omitted for the sake of clarity, but they are identical in character and functioning to the similarly situated mixing box and receiver circuit described and claimed in Patent No. 1,856,310. It will be clear that the insertion of the tube 5 between the line L², L³ and the antenna A substantially prevents any high frequency line control current from reaching the antenna, and any radiation of the control frequencies from the antenna is thus substantially prevented. Another modification is illustrated in Figure 2a from which it will be observed that the high frequency control currents generated in the control device C and transmitted therefrom over the light or power lines L² and L³ to the mixing box apparatus generally indicated at M are impressed upon the plate circuit of the detector tube 1 instead of being impressed upon the grid circuit of this tube as described in the patent aforesaid. If the high frequency control currents are of large amplitude, as is the case in the class of remote control systems herein considered, they will be rectified between the plate and cathode electrodes of the vacuum tube 1, the latter

acting in this respect as a two electrode rectifier as far as these plate impressed high frequency currents are concerned. As previously explained in connection with Figure 2, the antenna signal currents impressed upon the grid circuit of the tube 1 will be rectified therein, and thus rectified will appear in the plate circuit of the tube where they will mix with the rectified control currents to produce the required beat frequency for operating the receiver in accordance with the principles and features in the patent referred to. As in the previous modification of the invention as described in connection with Figure 2 it will be clear that by thus impressing the control currents in the plate circuit of the tube while impressing the antenna signal currents in the grid circuit thereof, the control currents are prevented by the one-way repeater action of the tube from reaching the antenna and interference by these control currents on neighborhood receivers is thus prevented. In Figure 2a, as in Figure 2, for the sake of clarity, certain circuit elements of the mixing box and the receiver associated therewith have been omitted, but nevertheless the attachment to the circuit elements shown will be clear to those skilled in the art by referring to the aforesaid patent.

A third modification which may be employed to prevent radiation of the control frequencies from the receiving antenna is shown in Figure 2b. In this arrangement, which for the sake of simplicity shows only the circuits of the detector or mixing tube 1, the control currents coming over the lighting lines (not shown in the figure) are fed to coil N through the leads X and Y and fixed condenser K¹, the latter being used to prevent short circuit of the low frequency (e. g. 60 cycle) line current. The control frequencies are inductively transferred from coil N to coil N' which is connected to the electrical center of coil 4 as shown which latter picks up incoming signal frequencies from the antenna A through its inductive relationship to coil O. The condenser K² is connected as shown and given a value equal to the equivalent capacity of the grid condenser 2 and the capacity of the grid to cathode of tube 1 in series; so that the impedance and phase angle of the upper circuit P¹, 2 P², N' is substantially equal to the impedance and phase angle of the lower circuit P¹, K² and P², N'. With this balanced arrangement it will be clear that the high frequency control currents induced in coil N' will divide equally between the upper and lower halves of coil 4. Half of the control current will flow upward in the upper half of coil 4 and half the current will flow downward through the lower half of coil 4 as indicated by arrows in the figure. These two portions of the control current therefore exactly neutralize each other in their effect upon the coil O which is so located as to be electrically influenced equally by the two halves of coil 4. Thus, no currents of the control frequencies appear in the antenna and neighborhood interference due to control frequency radiation from the antenna is avoided. While it is recognized that somewhat similar methods have been used in other devices and for other purposes, the design here disclosed for the specific purpose set forth is new and useful.

Cross-talk between circuits. (See Figure 3).— This type of interference may be experienced under the following typical conditions. Imagine two adjacent apartments separated by a wall with house light circuits for each apartment located in 75.

the separating wall, and each apartment equipped with a remote control system for radio reception comprising respectively the control units C^1 and C^2 , receivers and mixing boxes R^1 and R^2 , antenna A^1 and A^2 and grounds G^1 and G^2 . Under certain circumstances it may be found that the high frequency control currents flowing in the lighting circuit L^{11} , for example will affect the operation of the receiver in apartment #2 or vice versa. I have termed interference of this kind "cross-talk between circuits" because it would appear at first sight that any such interference is the result of induction between the two very closely adjacent line circuits L^{11} and L^{12} . The term is misleading, however, but its chief justification lies in the easy picturization of the effect suggestion; for I have discovered that the lighting lines L^{11} and L^{12} exhibit practically no radiation of high frequency energy whatever and furthermore that the effective coupling between them is negligibly small so that as a result any interference of one control system on the other is not caused by any direct cross-talk or line to line effect. I have discovered that when this type of interference or apparent cross-talk is experienced, the reason for the effect is that the two apparently independent lighting circuits are not in fact independent but are in some manner incidental to the wiring of the lighting system actually connected together as indicated generally by the dotted lines L . The path of this concealed connection may be quite circuitous and may pass through fuse blocks in the building, line switches, ground or accidental connections on the electric system, etc. but if such a path exists, the high frequency control currents generated by a remote control unit such as C^1 Figure 3, and impressed by it upon the lines will follow around the lines and connecting path referred to and cause interference in another radio receiving system such as R^2 .

It will now be clear that the remedy to prevent this type of interference is in general to segregate electrically each radio control system so that the high frequency control currents of each such system are prevented from passing along the light lines beyond that portion of the house wiring to be utilized in that particular system of remote control operation.

Figure 4 shows an arrangement used to accomplish the above result. In this figure there are shown, for the sake of clarity, two adjacent light or power line circuits L^{13} and L^{14} connected through line switches S^1 and S^2 , and fuse blocks F^1 and F^2 to a common power supply line L^5 which may run outside of the building to a pole line transformer. Remote control units C are indicated as plugged into the lines L^{13} and L^{14} and radio receivers R' with mixing boxes M' are also shown as connected to the lighting lines. The actual house wiring circuits will in general be much more complex than here indicated but the important fact is that in any system of two or more such lighting or power circuits there is a point of common connection between them at the main power supply line such as indicated at L^5 , and each such circuit is readily accessible at the point in the building where its meter, switch, and fuse blocks are located. At such points, therefore, I propose to insert isolating units so constructed and connected as to prevent the passage beyond them of the high frequency control currents. Such units are indicated at I in Figure 4 and their details of construction are shown in Figures 5 and 5a.

In Figure 5 the light lines coming from the portion of the lighting system in the building which is being used in the remote control radio operation are indicated at L^{13} . These are connected to the isolating unit I and then pass on to the line switch of the system at 8 and 9. The isolating unit comprises the inductance coils $8a$ and condensers $8b-8b$ connected as shown with the coils in series with the two sides of the line and the condensers across the line. Such a combination of coils and condensers when suitably designed in accordance with principles already known in the art will effectively prevent the passage of high frequency currents from the lines L^{13} to the points 8 and 9 and thus prevent the line to line cross-talk type of interference hereinabove referred to. It will be understood by those skilled in the art that other arrangements and combinations of inductances and capacities may also be effectively employed in this connection and located similarly in the system to accomplish the result.

A uniquely similar arrangement to that of Figure 5 which functions in the desired manner and which is more simple, is illustrated in Figure 5a. It will be seen that herein the grounded side 9 of the lighting line has no inductance coil in it, and that only one such coil $8a$ is here used and that is placed in the ungrounded side 8 of the line.

While the arrangements just described are generally suitable for preventing cross-talk, it has been found that in many cases the spiral inductance or choke coils referred to may be dispensed with altogether. I have discovered that this is possible when the electric light companies watt-hour meter separates the light line over which the remote control operation is being conducted from other circuits for the reason that such standard meters possess sufficient inductance within themselves to serve as choke coils and effectively prevent the undesired cross-talk phenomenon. In such cases it is usually satisfactory also to dispense with the use of condensers. In other words, when lighting circuits are separately metered the choking effect of the meters themselves to the high frequency control currents is in many cases sufficient to prevent the passage of the latter from one metered circuit to another and cross talk is thus automatically prevented without the use of additional apparatus.

Conjugate signal beats.—In order to explain the nature of this type of interference one may consider, for example, the case in which remote control operation is being conducted with respect to signals transmitted on frequencies within the present American broadcast band, viz, between 550 kilocycles and 1500 kilocycles, and assume that the radio receiver portion of the entire remote control organization is pretuned to, say 540 kilocycles, in accordance with the principles referred to in Patent No. 1,856,310. Now any signal within the broadcast band may be heard on the receiver by regulating the remote control frequency so that it differs from the desired incoming signal frequency by 540 kilocycles thus creating the 540 kilocycle beat frequency to which the receiver is responsive. Obviously, however, any frequency differing from the said signal frequency by 540 kilocycles, if superposed upon the desired antenna signal frequency will produce the same result, that is will produce a beat frequency of 540 kilocycles with the signal and accordingly

cause reproduction of the latter by the receiver. Going a step further, it is apparent that any two high frequency currents simultaneously impressed upon the mixing detector of the remote control system and differing from each other by 540 kilocycles will result in energy passing into the radio receiver, which as explained has been pretuned to this frequency.

Thus it appears that many pairs of broadcasting stations may cause interference with one another since the antenna pick-up organization of the remote control system is made substantially equally responsive to all broadcast frequencies and of these there are many conjugate pairs of frequencies differing by 540 kilocycles. Thus, a broadcasting transmitter using a frequency of 800 kilocycles may produce a 540 kilocycle beat frequency at the mixing detector with another broadcasting station using a transmission frequency of 1340 kilocycles. Similarly, a 710 kilocycle broadcaster, for example, may also produce a 540 kilocycle beat with a broadcaster using 1250 kilocycles; and other stations transmitting simultaneously may produce 540 kilocycle beats between themselves in the same way.

Obviously under these conditions many 540 kilocycle beat frequencies may be superposed upon one another in the receiver, each variously modulated in accordance with the speech or music characteristics of the various transmitting stations with the anticipated result that very serious interference may be produced in the form of unpleasant and unintelligible jumbling or intermixing of many programs from the output of the receiver. Furthermore, the situation would seem to be still further complicated by the presence in the system of another 540 kilocycle beat which is that produced by the remote control when it is adjusted to tune in various desired signals. The present invention permits the mitigation of the conjugate beat frequency interference described utilizing the circumstance, Federally regulated, that broadcasting transmitters use frequencies of evenly numbered kilocycles and are separated by ten kilocycles; it permits the elimination of this type of interference by using a beat frequency for remote control tuning which is higher than the frequencies used for the stipulated broadcasting; and it provides for the suppression of the interference described by a novel manner of using the mixing detector tube of the system.

For the mitigation of conjugate frequency interference I pretune the receiver element of the remote control system to a frequency which, measured in kilocycles, is an odd multiple of 5, such for example as 545 kilocycles. Now since broadcasting stations, in accordance with Federal regulations, use frequencies spaced ten kilocycles apart and have values, measured in kilocycles, which are even multiples of 5, it is clear that no pair of broadcast frequencies can combine to produce a beat frequency equal to that to which the receiver has been pretuned. The nearest beat frequency which can thus be produced will be 5 kilocycles different from the frequency to which the receiver has been tuned, and depending upon the sharpness or selectivity of the receiver itself therefore, conjugate signal beats will be more or less reduced in their interference effects upon the receiver.

For the elimination of conjugate broadcast frequency beats it is proposed to pretune the receiver to a frequency above the highest signal fre-

quency to be received. For example, in broadcast reception the receiver may be tuned to say 1520 kilocycles. Since the broadcast frequency band referred to runs from 550 to 1500 kilocycles it is clear that no conjugate frequencies exist within this band whose difference can be as large as 1520 kilocycles and in this way, therefore, the possibility of interference of the kind considered is eliminated.

For the suppression of conjugate broadcast frequency interference I employ the novel and useful expedient of polarizing the mixing detector of the system with a strong high frequency voltage in a manner such that the detector output varies in direct proportion to its input. This is accomplished by causing the detector to oscillate by the use of methods and principles well known in the art, or by impressing upon it a strong high frequency oscillation from another source such as from the remote control unit over the connecting light or power circuit. Certain circuit arrangements are also made at the detector, according to known principles which together with the polarizing voltage referred to cause the operation of the detector to take place on a linear portion of its effective rectification characteristic.

The action and principle involved will be clear by reference to Figure 6 in which the line O—P represents the effective rectification characteristic of the detector following a non-linear law near O for small impressed voltages and a practically linear law for large impressed voltages. The abscissas of this rectifier curve represent impressed voltages on the detector while the ordinates to the curve represent corresponding output currents from the detector.

Assume first, for example, that only two signal frequencies are impressed upon the detector; that they are impressed simultaneously; that, for the sake of simplicity, they are unmodulated, and that one has a frequency of say 800 kilocycles and the other 1340 kilocycles. The voltage resultant of these will be as shown at a with a beat frequency envelope of 540 kilocycles and as a result of rectification the detector output current will be as shown at b containing a 540 kilocycle component as indicated by the lower dotted line, and this 540 kilocycle component will thus be amplified by the receiver connected to the output of the detector, assuming, of course, that the receiver has been pretuned to 540 kilocycles. This is the condition that would be experienced when the detector is used in the ordinary conventional manner with non-linear response, and gives rise to the conjugate signal beat interference hereinabove described since any two signal frequencies differing by 540 kilocycles simultaneously impressed upon the detector will produce the 540 kilocycle variation in detector output current.

Now, however, if there is also impressed upon the detector the unmodulated high frequency polarizing voltage c of Figure 6 the action is entirely changed. The total voltage impressed upon the detector is now the sum of a and c, which after rectification results in the plate current d. It will be seen that in this plate current there are two 540 kilocycle components which are oppositely phased and as a result thereof no 540 kilocycle current reaches the amplifier. The effect of the polarizing oscillation therefore, and the resulting linear detector response causes complete suppression of the 540 kilocycle beat between the two representative signals of 800 kilocycles and

1340 kilocycles simultaneously impressed on the detector.

Cross modulation.—This is an interference effect which may manifest itself on a remotely controlled receiver of the class herein considered during the process of tuning in various stations when reception is being carried on in the vicinity of a high power broadcasting station. It is usually noticed only when the receiver is located within a mile or so of such a transmitter. It comprises a phenomenon not alone peculiar to remote control operation of a receiver but is also often encountered in the conventional operation of ordinary receivers. When it occurs the operator of the receiver will notice that while he may be able to tune out the strong local station by a relatively small adjustment of the tuning of the receiver, nevertheless when he successively tunes in other signals the local signals will be heard superposed upon the other station to which he tunes the receiver. In fact the local station may be heard at many different settings of the receiver tuning mechanism though only at such settings as may correctly tune in a station other than the local. This type of interference by a local station with another station though the two be using widely different transmission frequencies has been well known in the art for some time and it may, as stated, readily occur in remote control systems of the class herein considered in the following way:—

In such systems, the pick-up organization at the mixing detector comprising coils of the general class of 3 and 4 of Figure 1 and more fully described in Patent No. 1,856,310 constitutes an untuned or broad-band tuned receiving circuit connected to the antenna A and detector tube 1; and all antenna signals or broadcast programs within the band of frequencies which it may be desired to receive are hereby passed to the detector tube 1. By the process of detection these signals are broken up into currents of various component parts, there being produced, among other currents in the detector circuit, audio frequency currents of the various audible frequencies that were present in the modulation characteristics of the original incoming signal wave. This circumstance exists for all signals received upon the antenna. Now by the process of remote control tuning herein considered the carrier frequency of an antenna signal is changed by intermixing with the light line control frequency to a new (beat) frequency suitable for amplification by the receiving set and, as explained in the patent previously referred to, this new (beat) frequency first appears in the plate circuit of the mixing box detector tube 1, Figure 1. It will be clear, therefore, that the plate circuit of this tube contains currents of a great many different frequencies. Those of most importance, however, are the beat frequency just referred to as produced in the reception of some desired transmitting station, and any extremely strong audio frequency currents that may be produced by a powerful local transmitting station.

If the amplitude of the last mentioned audio currents is so great as to be ten percent or so of the amplitude of the beat frequency carrier current produced in the reception of another station then it will be readily understood that these audio currents will be sufficiently strong to modulate the beat frequency carrier current through the superposition of the two and the local station will therefore be audibly overlayed on the other station which it is desired to receive. This con-

stitutes the cross-modulation type of interference, the suppression of which is one of the objects of this invention.

To suppress this cross-modulation type of interference I make use of the linear detection action and polarizing oscillation hereinbefore described with reference to the suppression of conjugate signal beats, and through the use of the detector in this way cross-modulation is prevented in a manner entirely similar to the suppression of conjugate signal beats. The action and principle involved in this case will be clear by reference to Figure 7. In this figure the desired carrier frequency current, shown unmodulated, for the sake of clarity, is indicated at *a*. The polarizing oscillation, here assumed for convenience of drawing as differing from the desired carrier by 540 kilocycles is shown at *b*. The superposition of these and rectification of their resultant produces the detector output current *c* with high frequency envelope of 540 kilocycles. Under the assumption that the receiver has been pretuned to 540 kilocycles the desired signal carrier thus changed to 540 kilocycles will now be amplified by the receiver.

Now upon additionally impressing the modulated signal *d* which might normally be expected to produce cross modulation the output current from the detector obviously takes the form *e*, at least as far as the 540 kilocycle envelope is concerned, and it is at once evident that the latter is not modulated by the audio component of the interference signal.

As in the suppression of conjugate signal interference, it will be clear that here too the requirement for suppression of interfering signals is that the polarizing oscillation be of large amplitude as compared with the interference and that the detector response be linear rather than curved in the region of operation.

It will also be understood that the frequency of the polarizing oscillation may have any value so long as it is above audibility and does not produce audible frequency beats with any of the other frequencies involved in the operation of the system.

Image signals

The general nature of this type of interference may be made clear by the following example. Suppose that the receiver of the remote control system is pretuned to a relatively low frequency such as, say 175 kilocycles, instead of to the higher beat frequencies heretofore considered, and suppose it is desired to receive an 800 k. c. broadcasting signal according to the principle described by superposing upon this 800 k. c. signal frequency another frequency differing by 175 k. c. so as to produce a beat frequency of the latter value suitable for the pretuning setting of the receiver. The superposed frequency for this purpose may thus be 975 k. c., that is 175 k. c. above the desired signal frequency. It will be clear, however, that this superposed frequency of 975 k. c. can also produce a 175 k. c. beat with another broadcast signal of 1150 k. c. so that the latter as well as the desired 800 k. c. signal will both be amplified and reproduced by the receiver and thus cause interference. This is image interference, and the two broadcast signal frequencies of 800 k. c. and 1150 k. c. are said to be image frequencies. It is to be noted that they differ from one another by twice the value of the beat frequency used for tuning.

In the example just cited it is obvious that the reason for the existence of the image interference

as described for broadcast band reception, i. e. for reception of signals between 550 k. c. and 1500 k. c., is that the beat frequency employed is so low, that is 175 k. c.; and it follows equally clearly that such broadcast image interference can be prevented by selecting a higher beat frequency for the tuning process such as frequencies in the neighborhood of 540 k. c. or else above 1500 k. c. as have hereinbefore been discussed and fully explained in Patent No. 1,856,310.

When the beat frequency used is as high as say 540 k. c. it is impossible to experience broadcast images and the use of beat frequencies of this order of magnitude and for this reason is therefore an important, novel and useful feature of the present invention. Thus, if the beat frequency used for the tuning process is say 540 k. c. (i. e. the receiver is pretuned to 540 k. c.) the control beating or tuning frequencies used for broadcast reception will run from 1090 k. c. for 550 k. c. reception up to 2040 k. c. for 1500 k. c. reception and signal frequencies which would produce image interference accordingly lie between 1630 k. c. and 2580 k. c., a frequency band entirely outside of the broadcast range. It will be clear that in order to avoid broadcast image interference of the kind described the beat frequency used in the tuning process must be above 475 k. c. for at this frequency the tuning control frequency required for 550 k. c. reception would be 1025 k. c. which would bring in an interfering image at 1500 k. c., the lowest broadcasting frequency used.

While image interference within the 550 k. c. to 1500 k. c. broadcast band is impossible in the present system due to the use of relatively high beat frequency in the manner and for the reasons described, there is nevertheless the possibility of image interference from various short wave transmitting stations such as those used for picture transmission, amateur radio communication, etc. Thus, in the example above stated where a beat frequency of 540 k. c. is used, it was shown that image interference would be caused by transmitting stations using frequencies within the band 1630 k. c. to 2580 k. c. Similarly if the beat frequency employed is at the other end of the broadcast band, such for example at say 1520 k. c., then obviously short wave image interference is possible from transmitters using frequencies between 3590 k. c. and 4540 k. c.

In order to prevent short wave image interference of this kind I use, in one modification of my invention a low-pass filter in the antenna circuit preceding the mixing detector as indicated in Fig. 8. Herein A is the receiving antenna, G the ground, and the organization at M³ the mixing tube and input circuits as hereinbefore described. The low-pass filter is indicated generally at F³. It is designed according to principles well known in the art and in a manner such that frequencies below 1500 k. c. pass readily from the antenna to the mixing detector while frequencies above 1500 k. c. are substantially blocked out and prevented from reaching the detector. It is to be understood, of course, that the design described applies specifically to the case where the system is intended for the reception of the usual broadcast signals using frequencies from 1500 k. c. to 550 k. c. For other conditions of use the same filtering principle may be used for similar purposes and the design of the filter will be carried out according to known principles such that desired frequencies will be passed to the detector while interfering signals will be suppressed.

75 An alternative arrangement to that of Fig. 8

which also provides for the suppression of interference by short waves by preventing such short wave frequencies from reaching the mixing detector is shown in Fig. 9, where it will be seen that an additional vacuum tube V² is inserted between the antenna and the low-pass filter which latter may now consist, as shown, of the choke coil F³ and condensers C⁴ and C⁵. This arrangement has certain advantages over the arrangement of Fig. 8 in that the filter is hereby removed from the antenna circuit whose electrical characteristics may be such, as will be understood by those skilled in the art, as to reduce the effectiveness of the filter if placed directly in the antenna circuit. Furthermore, the arrangement of Fig. 9 with the filter and tube V² interposed between the antenna and the mixing detector V¹ assists in preventing radiation from the antenna of the high frequency control frequencies coming over the light lines and delivered thence to the circuits of the detector.

Harmonic interference

I have pointed out in my Patent No. 1,856,310 that in the operation of the remote control system as described, the circumstance that the ratio of maximum to minimum control tuning frequencies for broadcast reception is less than 2 to 1 prevents the possibility of interference which might otherwise result from a harmonic of the remote control oscillator producing a beat frequency suitable for amplification by the receiver of the system by combination of such a harmonic with another broadcast frequency other than the one which it may be desired to receive. It will be understood, however, that if the remote control oscillator generates harmonics, interference may be experienced thru the combination of such harmonics with short wave transmitters of the class referred to hereinabove with respect to short wave image interference, provided such harmonics produce a beat frequency or frequencies with such short wave signals equal to the frequency to which the receiver has been pretuned for remote control operation.

When such harmonic interference is experienced I prevent it by suppressing harmonic frequencies of the remote control oscillator by arranging that its output energy be substantially sinusoidal as to oscillation wave form. This may readily be accomplished by methods well known in the art. Alternatively for the same purpose I suppress the interfering short wave signals coming in on the antenna, and for this purpose use the same arrangements as shown in Fig. 8 and Fig. 9 hereinbefore described with respect to suppression of short wave image interference. It is to be understood therefore that the arrangements of Fig. 8 and Fig. 9 are employed to prevent both short wave image signals and short wave harmonic interference. This is possible because the short wave frequencies capable of producing harmonic interference lie in a range above approximately the value of any possible image frequency signals. Thus, for a 540 k. c. beat frequency at the receiver it has been shown that possible image producing frequencies for broadcast reception lie above 1630 k. c., whereas for this same receiver beat frequency the possible harmonic interference signals lie above 1640 k. c. because the remote control frequency required for the reception of the longest wave broadcasted which uses 550 k. c. is obviously 1090 k. c. of which the second harmonic is 2180 k. c. and the lowest short

wave signal frequency with which the latter can produce a 540 k. c. beat is obviously 1640 k. c.

Static and background interference.—This class of interference is commonly experienced in the operation of all radio receivers. In a remotely controlled receiving system, however, of the kind herein considered, a somewhat different situation is presented in respect to this kind of interference, and in connection with such systems

10 I use a simple expedient to minimize or reduce this interference.

This expedient embodies a detail in the method of operating the remote control system. If static, damped wave spark signals, or other background 15 interference or noise is present, I turn the volume control device of the receiving set down until such background noises are not annoying. This control is then left at that setting for the reception of all stations. This of course makes it impossible 20 to receive desired station signals by remote control as loudly as if the volume control on the receiver itself were turned up to maximum. However, under heavy static or bad background noise conditions it is not possible to use the volume control 25 on the receiver at its maximum position even in the conventional direct operation of the receiver, and it is plain therefore that as regards such interference the remote control system operated as described in reference to the permanent 30 adjustment of the receiver volume control device is on a par with the ordinary directly operated receiver. This detail of adjusting the receiver volume control as described is simple, but it is an interference preventing expedient in remote control 35 operation which may not be obvious.

While the method just described for minimizing static and background noise is useful and simple, it does not provide the flexibility afforded by the direct continuous operation of the actual 40 volume control on the receiver as normally practised in the conventional operation of the receiver to alter its sensitivity and thus limit the amount of background noise or static. The reason for this is that with the method described it 45 is clearly impossible by means of the remote control oscillations, to increase or decrease the sensitivity of the receiver itself. An improvement therefore upon the method described would be an arrangement permitting actual control of the 50 sensitivity of the receiver itself.

One modification of such an arrangement which I have employed is shown in Fig. 10, which shows the elements at the receiver essential to the accomplishment of the object stated. The 55 remote control unit (not shown in the figure but constructed and used generally according to the principles described in my Patent No. 1,856,310) generates a suitable high frequency current to be used for controlling the sensitivity or "gain" 60 of the receiver. This control current is delivered to the receiver organization over the leads *x* and *y* and thence to the circuit LC which is designed to be responsive to the said control current. The latter circuit is connected as shown to the auxiliary 65 rectifier tube *T*. The high frequency control currents are thus rectified at *T* and according to well known principles produce a continuous D. C. potential across the resistance *R*. A portion of the circuits of the radio frequency 70 amplifier of the receiver is shown connected to this resistance, and it will be clear from the drawings that thru the connections of the amplifier to the resistance *R* the D. C. voltage drop thru the latter will affect the grid bias voltage on the 75 tubes of the amplifier and hence the amplifica-

tion of the latter. The larger the amplitude of the high frequency control current (this being controllable at the remote control point according to the principles explained in my Patent No. 1,856,310) the greater will be the D. C. voltage across the resistance *R* and hence the greater the negative bias on the tubes of the amplifier in the receiver; and the smaller the amplitude of the control current the less will be the amplifier tube bias. It will thus be clear that by 10 suitably locating the tap *P* permanently on the resistance *R* a condition may readily be established such that when the control current referred to is of zero amplitude the bias voltage on the amplifier is correct for maximum receiver 15 amplification, while with large control current amplitude this bias voltage assumes a sufficiently large negative value to prevent amplification by the tubes of the receiver. The actual receiver sensitivity is thus altered by changing the amplitude of the control oscillation at the control point which in turn changes the grid bias of the amplifier. Immunity from background noise and static, as well as volume control of the receiver is thus achieved by an actual change in receiver 20 performance entirely similar to that by normal direct operation of the receiver by means of its own controls.

A variation of the arrangement just described is shown in Fig. 11, but works in the reverse way. 30 That is, in the arrangement of Fig. 11 the strength of signal delivered by the receiver, or otherwise stated, its sensitivity decreases with decreases made in the amplitude of the control oscillation at the remote control point. This has 35 certain advantages over the method illustrated by Fig. 10 in that it permits the use, if desired, of the tuning currents generated and operative according to the principles of my Patent No. 1,856,310 for remote control of receiver sensitivity as well. As these tuning currents are reduced at the remote control point the signal strength at the receiver is decreased for two reasons. First the volume is reduced because the amplitude of the beat frequency at the receiver 45 resulting from the mixing of the control tuning current and the antenna signal current is reduced, and second, the grid bias on the receiver amplifier tubes becomes more negative due to the increase in the plate current of the leaky grid 50 volume control rectifier tube *D* thru resistance *R*, Fig. 11, which reduces the amplification of the receiver.

I shall now describe in detail a modification of the present invention comprising a complete 55 remotely controlled receiver system in which all of the several features for preventing the various kinds of interference hereinbefore described are included. Reference is made to Fig. 12. At RFA is shown a portion of the conventional circuits of the radio frequency amplifier portion of a radio receiver. These circuits are connected as shown to an organization of auxiliary circuits which include among other elements the mixing detector tube 10 and the volume control tube 11, each 60 with their respective grid condensers 12 and 12' and grid leaks 13 and 13'. The batteries B¹, B², B³ are merely shown as such to indicate the points in the circuits where plate voltage is supplied to the several tubes, and it will be understood that in a receiver organization operating from the light socket these plate voltages will not be furnished by batteries but will be derived from rectified and filtered alternating current according to principles and methods well known in the 65 70 75

art. The remote control unit is indicated at C and in accordance with the principles of my Patent No. 1,856,310 is arranged to generate simultaneously a certain fixed frequency of invariable amplitude and also other frequencies used for tuning, variable at will by the operator for tuning in various stations at the receiver, and adjustable in amplitude to regulate the volume or strength of signals reproduced by the receiver.

10 Both the fixed frequency and the tuning frequencies just referred to are sent over the lighting lines L² and L³ to the receiver organization where they are injected into the latter thru coils 14 and 15 acting inductively respectively upon 15 the associated coils 14' and 15'. The latter are in the central leg of the bridge circuit comprising tube 10, center tapped coil 16 and condenser 17 arranged as hereinbefore described to prevent radiation from the antenna of any control 20 current frequencies. The tuning frequencies are introduced into the receiver circuits thru the coil combination 14-14', while the fixed frequency from the control point is introduced into the receiver circuits thru the coil combination 15-15', 25 the latter being tuned to the said fixed frequency by means of condenser 18. The antenna signal currents are led to coil 16' from the antenna A thru the low-pass filter consisting of coils 19-19 and condensers 20-21-22 as hereinabove de- 30 scribed with reference to and for the purpose of suppressing short wave image and harmonic interference. Since the circuit 15'-18 is tuned as stated to the fixed frequency delivered from the control unit a considerable high frequency voltage of this fixed frequency is developed across this circuit, and this steady high frequency voltage continuously applied to the detector tube 10 as will be clear from the drawings serves to polarize the detector tube 1 and suppress both cross- 35 modulation interference and interference from conjugate signal frequencies in the antenna in accordance with the principles hereinabove explained with reference to the elimination of these types of interference. In series in the tuned 40 circuit 15'-18 is the thermal switch 23 operative according to the principles explained in my Patent No. 1,856,310 which as shown in the drawings Fig. 12 closes the circuit to supply power to the entire receiver organization. Radio frequency 45 choke coils 24 are inserted at the points in the circuits shown to prevent the passage of high frequency currents into portions of the system from which it is obviously necessary to exclude them. The input voltage to the volume control 50 tube 11 is the voltage developed across the coil 14' by the tuning currents from the remote control point, this voltage being impressed upon the tube 11 thru the lead wire 25. When the amplitude of the tuning currents fed into the line at 55 the remote control point is reduced the beat frequency tuning current produced by detector tube 10 fed to the receiver amplifier thru condenser 26 decreases and hence reduces the volume of whatever signal has been tuned from the control point. 60 At the same time this decrease in tuning frequency amplitude reduces the high frequency input to the volume control tube 11, increases the plate current of this tube thru the resistance 27, 65 accordingly increases the grid bias on the amplifier portion of the receiver, and hence reduces the receiver sensitivity so that all signals including those produced by static or other background noise are reduced, and vice versa when 70 the tuning currents from the control point are 75

there increased in amplitude, the signals from the receiver are increased.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims. 10

I claim:—

1. In a remotely controlled radio receiving system adapted to be controlled over an electric power supply line, the combination of a receiver having an antenna input circuit, and signal reproducing apparatus, control means for controlling said receiver, means for coupling said control means to the power supply line at a point remote from said receiving apparatus, said control means including means for generating high frequency currents of various frequencies for rendering said receiver responsive to signal energy of different frequencies and means for generating a high frequency control current of fixed frequency, both of which currents are impressed on the power supply line, coupling means for connecting the signal input circuit of said receiver to an electric power supply line and means connected to the input circuit of said radio receiver for preventing radiation of any of said control current frequencies from the antenna of said receiver. 15 20 25

2. In a remotely controlled radio receiving system adapted to be controlled over an electric power supply line the combination of a receiver having an antenna input circuit, and signal reproducing apparatus, control means for controlling said receiver, means for coupling said control means to the power supply line at a point remote from said receiving apparatus, said control means including means for generating high frequency currents of various frequencies for rendering said receiver responsive to signal energy of different frequencies and means for generating a high frequency control current of fixed frequency, both of which currents are impressed on the power supply line, coupling means for connecting the signal input circuit of said receiver to an electric power supply line; and means connected to the input circuit of said receiver, including a tuned circuit 30 35 40 45 50 55 60 65 70 75 80 85 90 95 100

3. In a remotely controlled radio receiving system adapted to be controlled over an electric power supply line, the combination of a receiver having an antenna input circuit, a detector tube, and signal reproducing apparatus, control means for controlling said receiver, means for coupling said control means to the power supply line at a point remote from said receiving apparatus, said control means including means for generating high frequency currents of various frequencies for rendering said receiver responsive to signal energy of different frequencies and means for generating a high frequency control current of fixed frequency, both of which currents are impressed on the power supply line, coupling means for connecting the signal input circuit of said receiver to an electric power supply line; and means connected to the input circuit of said receiver including a tuned circuit tuned to the fixed frequency delivered from the control means 75 80 85 90 95 100

to supply a steady high frequency voltage to said detector tube of said receiver for polarizing said detector and suppressing cross-modulation interference and interference from conjugate signal frequencies in the antenna.

5 4. In a remotely controlled radio receiving system adapted to be controlled over an electric power supply line the combination of a receiver having an antenna input circuit, a detector tube, and signal reproducing apparatus, control means for controlling said receiver, means for coupling said control means to the power supply line at a point remote from said receiving apparatus, said control means including means for generating 10 high frequency currents of various frequencies for rendering said receiver responsive to signal energy of different frequencies and means for generating a high frequency control current of fixed frequency, both of which currents are impressed on the power supply line, coupling means for connecting the signal input circuit of said receiver to an electric power supply line; and means connected to said coupling means for selecting and impressing high frequency potentials generated at said control means on the input circuit of said volume control tube for controlling the operation thereof.

15 5. In a remotely controlled radio receiving system adapted to be controlled over an electric power supply line the combination of a receiver having an antenna input circuit, a detector tube, a volume control tube, and signal reproducing apparatus, control means for controlling said receiver, means for coupling said control means to the power supply line at a point remote from said receiving apparatus, said control means including means for generating high frequency currents of various frequencies for rendering said receiver responsive to signal energy of different frequencies and means for generating a high frequency control current of fixed frequency, both of which currents are impressed on the power supply line, coupling means for connecting the signal input circuit of said receiver to an electric power supply line; means including a tuned circuit tuned to the fixed frequency delivered from the control means, in circuit with said radio apparatus to suppress cross-modulation interference and interference from conjugate signal frequencies in the input of said receiver, and a thermal switch connected in series with said tuned circuit for controlling the power from the power lines to said receiver.

20 6. In a remotely controlled radio receiving system adapted to be controlled over an electric power supply line the combination of a receiver having an antenna input circuit, a detector tube, a volume control tube, and signal reproducing apparatus, control means for controlling said receiver, means for coupling said control means to the power supply line at a point remote from said receiving apparatus, said control means including means for generating high frequency currents of various frequencies for rendering said receiver responsive to signal energy of different frequencies and means for generating a high frequency control current of fixed frequency, both of which currents are impressed on the power supply line, coupling means for connecting the signal input circuit of said receiver to an electric power supply line; and means connected to said coupling means for selecting and impressing high frequency potentials generated at said control means on the input circuit of said volume control tube for controlling the operation thereof.

25 7. A remotely controlled radio receiving system comprising in combination, a radio receiver having an antenna and being connected to electric light or power lines, means for generating high-frequency currents of various frequencies at a point remote from the said receiver, means for coupling said generating means with the light or power lines, means at said remote point for varying the strength of said high-frequency currents, 30 means in circuit with said receiver circuits and with said power or light lines comprising a rectifier, means for connecting said rectifier to said radio receiver for controlling the amplification thereof, means for impressing certain of the 35 remotely generated high-frequency currents on the power lines, means for impressing high-frequency signal voltages from the antenna upon the input of the circuits of both the aforesaid rectifier and thermionic tubes, filter means having predetermined electrical characteristics connected in circuit with the antenna and adapted substantially to prevent the flow of undesired ones of said high frequency currents into the antenna, and means connected with the receiver apparatus and responsive to high-frequency currents generated at the said remote point adapted to close or open the light or power line supply circuit to the said receiver apparatus.

ALBERT S. BLATTERMAN.
